UNITED STATES PATENT OFFICE.

GEORGE R. STETSON, OF NEW HAVEN, CONNECTICUT.

IMPROVEMENT IN MACHINES FOR MAKING BULLETS.

Specification forming part of Letters Patent No. 133,066, dated November 12, 1872.

To all whom it may concern:

Be it known that I, GEORGE R. STETSON, of New Haven, in the county of New Haven and State of Connecticut, have invented a new Improvement in Machine for Swaging Bullets; and I do hereby declare the following, when taken in connection with the accompanying drawing and the letters of reference marked thereon, to be a full, clear, and exact description of the same, and which said drawing constitutes part of this specification and represents, in—

Figure 1, a front view; Fig. 2, a sectional side view; and in Fig. 3, a vertical longitudinal section on line *xx*.

This invention relates to an improvement in machines for forming bullets by the process of swaging—that is to say, a machine in which a lead blank is swaged into the form required for the bullet. In this class of machines it is necessary that there be an opening in the die or follower through which the surplus lead may escape; but this necessitates the trimming of such surplus lead from the bullet after it is formed. The object of this invention primarily is to allow for this escape and trim the surplus lead from the bullet while in the die; and it consists in forming a vertical perforation in the follower eccentric to the center, into which perforation the surplus lead will pass, and after the follower has performed the work of compression a partial rotary movement is imparted thereto, which causes the follower to turn upon the end of the bullet, and the perforation, which is eccentric to the axis of the follower, turns out of position where the surplus entered and cuts from the bullet the surplus which it contains, thus allowing the bullet to be discharged from the machine complete and perfect. My invention also consists in the mechanism hereinafter described for supplying the blanks for the operation of the follower.

A is the bed of the machine, within which, at *a*, are arranged the usual dies for forming the bullet. Above this, in suitable bearings *B B*, is arranged the follower *C*, and to which a vertical movement is imparted from the driving-shaft *C¹* through a crank and lever, *C²*, or otherwise, so that a blank being placed in the die and the follower forced there-

on will compress the bullet in the usual manner. In the lower end of this follower I form a vertical perforation or opening, *d*, (see Figs. 2 and 2^a;) this perforation being eccentric to the axis of the spindle, and opening out at some point above, as denoted in Fig. 2. To this follower at the proper time, as hereinabove described, a rotating movement is imparted by means of a cam, *D*, actuating a slide, *D'*, (see Figs. 2 and 2^a;) the said slide in moving back and forth being in connection with the follower causes it to rotate accordingly. As the follower strikes the lead blank and compresses it the lead, more than is required for the bullet, will be forced up through the perforation *d* in the follower until a bullet is completely formed, then the before-mentioned rotary movement is given to the follower, causing it to turn upon the end of the bullet, and as the perforation *d* is eccentric to the axis of the follower this perforation is carried off from this point on the bullet, and in so doing cuts the surplus which is in the perforation smooth and clean from the bullet, then the ball is discharged in the usual manner. Thus the bullet is completed, and comes from the machine requiring no further operation.

To automatically supply the blanks for the action of the follower, a slide, *L*, is arranged longitudinally on the machine in suitable guides, and actuated by suitable mechanism to impart a longitudinal movement thereto, here represented as from a crank-wheel, *N*, the said slide fitted with an opening, *b*, as seen in Fig. 3, to receive the blank in one position, and by its longitudinal movement to carry this blank beneath the follower to deliver the blank to the die. With this slide is combined a vertical tube, *P*, denoted in solid black, Fig. 3, this tube extending to near the mouth of a hopper, *R*. Over this is a sleeve, *S*, arranged to slide freely on the tube *P*, and is in connection, by an arm, *T*, with the follower, so that as the follower rises and falls this sleeve rises and falls with it. The upper end of the tube *P* is formed or cut at an angle, as seen in Fig. 3, leaving no point upon which a blank may rest. The sleeve *S* passing up and down over the end of this tube, as denoted in broken lines, Figs. 2 and 3, constantly agitates the

mass of blanks in the hopper around the end of the tube, thus causing the blanks to follow each other successively into the tube P. This tube P stands directly over the opening b in the slide L, so that when the opening comes beneath the tube it takes a blank therefrom and transfers it to the die, then returns for a second, and so on.

I have represented the follower as having a reciprocating and rotating movement with stationary dies; but it will be evident to those familiar with machinery of this character that the same result will be attained by a stationary follower and reciprocating and rotating die, or these movements may be imparted to one or the other, or both.

I claim as my invention—

1. In a machine for swaging bullets, consisting of the follower C and the usual die, one or either or both having a reciprocating movement, the perforation d in the follower, combined with mechanism to rotate the said follower, substantially as and for the purpose set forth.

2. In combination with a follower and die for swaging bullets, I claim the tube P and reciprocating sleeve S and slide or carrier L, substantially as and for the purpose set forth.

GEORGE R. STETSON.
